(57) **CLAIM**

The ornamental design for seating furniture, as shown and described.

DESCRIPTION

FIG. 1 is an isometric view of seating furniture, in the form of a chair, incorporating our new design, wherein the break lines indicate indeterminate length;

FIG. 2 is a side elevation view thereof;

FIG. 3 is a front elevation view thereof, wherein the break lines indicate indeterminate length;

FIG. 4 is a top plan view thereof, wherein the break lines indicate indeterminate length; and,

FIG. 5 is a rear elevation view thereof, wherein the break lines indicate indeterminate length.

The broken lines shown in the drawings are for illustrative purposes only and form no part of the claimed design.

1 Claim, 3 Drawing Sheets
